BUTT-SEAMED METAL TUBE AND METHOD OF MAKING THE SAME.

1,019,485.

Specification of Letters Patent.

Patented Mar. 5, 1912.

Application filed July 27, 1910. Serial No. 574,076.

To all whom it may concern:

Be it known that I, ROBERT KOENIG, a citizen of the United States, and resident of Brooklyn, in the county of Kings and State 5 of New York, have invented new and useful Improvements in Butt-Seamed Metal Tubes and Methods of Making the Same, of which the following is a specification.

My invention relates to the construction 10 of prismatic sheet metal tubes, and consists in a method of forming butt seamed tubes of sheet metal, and in the tube which is the product of the said method.

The object which I have in view is to make 15 prismatic metal tubing which, though simply formed with a butt seam, without welding or swaging, shall present the appearance of a seamless tube, be amply strong for many light structural purposes, and cheaper than 20 welded, swaged or seamless drawn tubes.

Whenever a strip of sheet metal which possesses any appreciable resiliency is bent to form a tube, the metal is strained beyond its elastic limit through a progressive series 25 of shapes, until the two edges of the strip meet, when the residual elasticity of the metal suffices to spring the edges of the seam apart. By my invention the operation of rolling and drawing the tube produces in it 30 such internal strains that the normal condition at the seam is one of mutual pressure between the meeting edges, so that the tube is and remains a closed tube.

The essence of the method is the production 35 by rolling or drawing the metal, of longitudinally disposed narrow regions wherein the metal is in a condition of permanent internal strain, of which the resultant is a bending moment which tends to alter the 40 periphery of the tube as a whole and therefore closes the seam tightly, and likewise, the characteristic which distinguishes my new product, is the presence in the structure of a butt-seamed, sheet metal tube, of such 45 longitudinally disposed narrow regions of internal stress.

The mechanism by which the method is performed and the structure produced, which mechanism forms the subject matter 50 of an application for Letters Patent of the United States divided herefrom Serial No. 615,542, filed March 20, 1911, is characterized by an internal mandrel and external complementary die-members, which are all

so proportioned and disposed as to have internal and external clearances at the places where the angles of the prismatic tube are formed, and to exert forming pressure on the sides of the prismatic tube so as to cause a flow of the metal of which the tube is composed, from each side outward toward the clearance-spaces wherein the angles of the tube are formed. 55

The structural condition presented by a butt-seamed, sheet metal tube having longitudinally disposed narrow regions of internal stress may be, and I believe is best, produced by compressing the tube at intervals around its periphery, between the dies or rollers on the one hand, and an internal 65 mandrel on the other, so that the metal flows slightly in both directions out of the compressed regions, each local flow meeting an oppositely directed flow proceeding from an adjoining region of compression. The 70 meeting place of these two opposed flows of metal thus becomes a region of internal strain which when the tube emerges from the restraint of the instruments which formed it, holds the two edges of the seam 75 tightly pressed together, producing an apparently seamless tube, instead of the open-seamed tube which would otherwise result from the operation of the residual elasticity in a tube simply rolled up in the manner 80 heretofore practiced. Such a tube will be in a substantial sense prismatic, although the number of locally strained longitudinal narrow regions may be so large that the tube when finished is nearly cylindrical, so 85 nearly so that a coat of enamel will produce apparently true cylindricity. 90

In particular, however, my invention has for its object the production of obviously prismatic tubes, and will be adequately understood from a description of the method of forming a square tube, of the instruments used to carry out the method, and of the structure of the tube itself. 95

A concrete example of my invention is 100 illustrated in the drawings hereto annexed, in which—

Figures 1^a to 1^c represent diagrammatically three preliminary stages of the manufacture of a prismatic tube out of flat sheet 105 metal; Fig. 2 represents, partly in cross section, on a larger scale, the instruments for forming a square tube, and the tube therein;

and Fig. 3 represents in perspective, on a small scale, a piece of finished square tube.

I have found it desirable for practical purposes to form a cylindrical tube of sheet metal as a preparatory step toward the final construction of a prismatic butt-seamed tube. This preparatory step is illustrated in Figs. 1^A to 1^C inclusive, Fig. 1^A showing a cross section of a strip of metal which is to be formed into the tube. This strip will have been cut with shears which leaves a projection or bur indicated at *b* along the cut edges on one side of the strip. For purposes presently to be explained, I so place the strip of metal in the bending machine that when the cylindrical tube is formed, the burs lie on the outside. The formation of the cylindrical tube involves a rolling and drawing in any of the well known machines suited to the purpose, which first shapes the tube in channel form having a rounded U section as indicated in Fig. 1^B, and then further rolls and draws the metal so that the cylindrical tube shown in cross section in Fig. 1^C is the result. The mandrel and die which give the final cylindrical shape to the metal bring the two edges of the strip close together, but then the residual elasticity of the metal causes the two edges of the seam to spring apart slightly leaving a gap such as shown at *g* in Fig. 1^C. The cylindrical, open-seam tube is then placed in the machine which is to convert it into a prismatic tube with a closed butt seam.

For purposes of illustration, I take the case of a square tube to be made from the round tube above described. A draw-bench machine such as used for squaring seamless drawn tubing, will serve my purpose, with changes in the mandrel and roller dies, as hereinbelow described. The tools or instruments in the machine for forming the square tube which immediately perform the work, consist of an internal mandrel marked M in Fig. 2 and a roller die or former composed of four external rolls R which are opposed to the sides of the mandrel. This mandrel is held in position by a rod M² which is laid in the cylindrical tube of metal and is anchored outside the end of the tube to a convenient portion of the frame of the drawing machine. The forward end of the tube is gripped by the traveling jaws of the drawing machine in the usual manner. The arrangement of four rolls which constitute the external former or die is in general the same as that shown in Figs. 1 and 2 of Carr's United States Patent No. 402,140, and the positional relationship of the mandrel and sheet metal tube to each other and to the rolls is much the same as that shown in Fig. 1 of Ostrander's United States Patent No. 113,332.

65 The mandrel M and rolls R operate upon

all portions of the metal tube except at and near the corners of the prism which is formed by the rolling and drawing operation. Thus the edges of the rolls R as shown in Fig. 2 are well inside of the salient angles 70 of the square tube and the edges of the mandrel M are chamfered off at the corners at *m*', so that the active pressure and drawing friction is exerted on the inside by the sides *m* of the mandrel M and on the outside by 75 the rolls R.

The provision of clearance between the operating instruments at the corners thereof or rather at the places where the salient angles or edges of the tube are formed, together with the heavy pressure brought to bear between the mandrel and the rolls bends and compresses the metal of which the round tube was formed and which is being squared in the machine, at the sides of the squared tube and this causes a flow of the metal of which the tube is composed from the sides toward the angles, the direction of this flow being indicated by the arrows in Fig. 2. Therefore at each corner C of the square 90 tube the flow of metal coming from two directions produces a region which is set in compression at each salient angle of the tube; these compression regions are indicated conventionally by heavy shading at the 95 points C in Fig. 2.

The dimensions of the mandrel M and rolls R are properly adapted to the peripheral dimensions of the round tube shown in section at Fig. 1^C, so that in forming the 100 prismatic tube the edges of the gap *g* are brought together. But when the prismatic tube has been formed as above described, the presence at the salient angles of the tube of regions in which the metal of which the tube 105 is formed is under internal compressive strain produces a resultant of contractile effort as contrasted with the residual expansive elasticity manifest in the round tube shown in Fig. 1^C, and the edges of the 110 seam at *g* are held in close mutual abutment. As the burs *b* were left at the outside of the tube, these are rolled into the seam *g* so as to fill the slight irregularities due to imperfect cutting of the strip in the first place. 115

Butt-seamed prismatic tubes formed as above described present to the eye the appearance of seamless drawn tubes and are amply strong for many light structural purposes, such as the manufacture of metal bedsteads or other furniture, and by reason of the simplicity of their method of manufacture, can be made more rapidly and cheaply than seamless drawn, brazed, or welded tubes. Close scrutiny of a prismatic tube 120 formed as above described may detect the butt seam, but as metal tubes of this kind will usually be coated, painted, or enameled, the butt seam will entirely disappear from view in the final product. 125

What I claim and desire to secure by Letters Patent is:

1. The method of making butt-seamed tubes, which consists in bending a sheet of metal into tubular form and then producing in the sheet a permanent peripherally contractile internal strain.
2. The method of making butt-seamed tubes, which consists in bending a metal sheet into prismatic tubular form and producing in the metal of the sheet at the salient angles of the prism a permanent, internal, compressive strain.
3. The method of making butt-seamed prismatic metal tubes, which consists in bending a strip of metal into the desired tubular form, and compressing the metal at the sides of the prism causing internal flow toward the salient angles sufficient to produce at

said angles a condition of permanent internal compressive strain. 20

4. A tube consisting of a sheet of metal bent in prismatic form with edges in one of the faces of the prism abutting under mutual pressure. 25

5. A tube consisting of a bent sheet of metal in prismatic form with abutting edges on one of the faces of the prism, the material of which the sheet is composed being under permanent internal compressive strain at 30 the salient angles of the prism.

Signed by me at Brooklyn Kings Co. New York this 20th day of July 1910.

ROBERT KOENIG.
